N.C. Willett,

Bread Machine,

Patented Dec. 28, 1832.

Nimrod C. Willott of Frenchborough Tennessee
Sitter's Patent

The Schedule referred to in these letters patent and making part of the same containing a description in the words of the said Nimrod C. Willott himself of his improvement in the machine for spreading Dough.

To all to whom these presents shall come. Be it known that S. Nimrod C. Willott of the Town of Frenchborough in the County of Washington and State of Tennessee. has invented a new and useful improvement for Spreading Dough and that the following is a full and exact description of the construction and operation of the said machine as invented by me to wit.

Plated nut placed one above the other in upright standards at each side of the table, the leaves of which are placed near to the lower roller or nut, with a judgment to extend through one of the uprights with a crank or handle by which the upper nut is revolved and thereby the dough is compressed between it and the lower one and carried through in the direction in which the roller nuts are turned and thus compressed between the nuts, thrown upon the leaf at the opposite side from whence it comes.

The table upon the sides of which the uprights are affixed is of the ordinary construction except that the legs are both mortised by tenons and dovetail, and the uprights confined by a key extending the whole width of the table frame.
